CHARLES BEMIS REARICK, OF NEW LONDON, CONNECTICUT.

ELASTIC-FLUID TURBINE.

1,156,371.

Specification of Letters Patent.

Patented Oct. 12, 1915.

Application filed March 9, 1914. Serial No. 823,398.

To all whom it may concern:

Be it known that I, CHARLES BEMIS REARICK, a citizen of the United States, and resident of New London, county of New London, State of Connecticut, have made a certain new and useful Invention Relating to Elastic-Fluid Turbines, of which the following is a specification, taken in connection with the accompanying drawing, which 10 forms part of the same.

This invention relates especially to elastic fluid turbines in which the turbine wheel may be provided with friction drive members and also with impulse blades to act 15 upon the motive fluid after it has been engaged by the friction drive members if desired. The friction drive members or plates may be in the form of substantially circumferentially arranged rings, if desired, and 20 closely spaced between primary impulse members or vanes which may interlock with the drive plates and exert a mutually retaining action thereon and also serve to guide the motive fluid in a somewhat curved 25 path as it moves forward and across the wheel before being engaged by the impulse blades which absorb still further energy therefrom. The friction drive plates and the primary impulse vanes and impulse 30 blades may be arranged between and secured to the wheel rim and a heavy strengthening shroud ring on the outside to give the wheel increased strength.

In the accompanying drawings showing 35 an illustrative embodiment of this invention in a somewhat diagrammatic way, Figure 1 is a vertical axial section through a turbine. Fig. 2 is an enlarged sectional view showing a nozzle member and coöperating wheel portions. Fig. 3 is a somewhat diagrammatic transverse section through the wheel portion 40 shown in Fig. 2 the line of section passing between the sets of impulse vanes. Fig. 4 is an enlarged detail cross-section taken substantially along the line 4—4 of Fig. 2. Fig. 5 is a transverse section showing another form of turbine wheel in which a second set of impulse blades are employed beyond an interposed set of stationary guide 45 blades.

The turbine casing may be of any desired 50 form and construction, such for example, as indicated in Fig. 1 as comprising the longitudinally divided casing having a series of partitions, such as 2, 10, to form the desired number of wheel chambers in connection

with the corresponding partitions, such as 3, in the other section of the casing. The steam may be admitted in any suitable way to the steam chest or admission passage 4 50 which may be integral with the wheel casing which may also be provided with an exhaust passage 14 integral therewith, if desired. The casing may be formed with suitable recesses in which the packing or bearing 55 members 7 may be supported to coöperate properly with the turbine shaft 1 on which the desired number of wheels 8, 9 may be arranged in any suitable way. A series of the desired number of nozzle members, such 60 as 5, may be arranged to coöperate with the primary wheel 8 and a similar series of secondary nozzle members 12 may be arranged to coöperate with the lower pressure wheel 9 and these nozzle members may be supported 65 in any suitable way in connection with the wheel preferably by mounting the nozzle members in suitable aligned nozzle apertures bored or otherwise formed so as to extend longitudinally through the casing sections. 70 The nozzle members 5 may for instance be secured in aligned position by suitable bolts, such as 50, or if desired a suitable bushing such as 11 may project through the corresponding nozzle aperture and be threaded or 75 otherwise secured to one of these nozzle members, such as 12, and then be brought up into the desired aligned holding position by the set screws or other fastening means 80 85 indicated in connection therewith. 90

Each of the turbine wheels which may be formed of any suitable material and shape may comprise a wheel center or supporting plate, such as 8, so as to hold the wheel rim 48 firmly and support the friction drive 95 plates and other members which may be mounted in connection therewith. It is desirable in most cases to have a suitable shroud ring, such as 20, which may be efficiently formed of nickel, steel or the like 100 secured around the wheel members so as to hold them in position and to form a more or less flaring passage across the wheel between the shroud ring and the wheel rim itself. In this way any friction drive plates or members may be conveniently mounted 105 in this flaring passage and may be effectively arranged and held in the desired closely spaced relation by any suitable means and it is of course understood that it is not necessary in all cases that these friction drive plates should be of exactly circumferential 110

or ring form although by welding or otherwise suitably uniting the ends of these plates to form substantially continuous rings the wheel strength is promoted. As shown in Fig. 3 it is desirable to have the receiving ends 23 of the friction drive plates 22 which may be suitably sharpened or beveled for greater efficiency also arranged so that they are stepped back in some suitable way with-
10 in the flaring wheel passage so as to prevent undesirable reduction of the effective passage area adjacent its receiving portion which may coöperate with the series of nozzles, such as 6, which may be of the flaring
15 expansion type. As shown in Figs. 2 and 3 the receiving ends of these friction drive plates may be stepped back on the outer and inner sides of the wheel passage so as to form an inclined stepped back arrangement
20 as indicated which progressively interposes more and more of these friction drive blades in the path of the motive fluid entering the flaring wheel passage and passing through the narrow fluid channels 27 which are made
25 sufficiently narrow or otherwise arranged so as to give the desired amount of frictional engagement or grip between the steam and these frictional drive members. It is desirable in some cases to have the discharge
30 ends 24 of these friction drive plates out of line or stepped back and the inclined stepped back arrangement of the lateral plates may be used in this instance also as shown in Fig. 3. It is desirable to have the
35 direction of the steam jets acting on these friction drive members such as to make a relatively low angle with the direction of movement of the wheel so as to utilize a correspondingly large proportion of the driving effect exerted on these frictional members by the motive fluid.

A convenient and desirable way to space these friction drive plates apart is to interpose between them suitable spacing members which are preferably given a suitably curved form so as to simultaneously act as impulse vanes or members and guide the steam passing between the drive plates across the wheel in the desired way. These
45 impulse vanes, such as 31, may be formed of somewhat flexible sheet metal of suitably curved form so as to utilize the desired amount of impulse driving action of the motive fluid and these impulse vanes may be of such width throughout their various portions as to secure a considerable lateral flaring of the thin channels between them as the motive fluid moves across the wheel and thus allow for the extent of velocity reduction effected during this pass. It is desirable to have suitable retaining or interlocking members formed on these impulse vanes and the coöoperating friction drive plates and this may be conveniently arranged by stamping up suitable retaining

lugs, such as 28, on the impulse vanes and forming correspondingly spaced sockets 29 in the drive plates 22 so that the entire series of drive plates and interposed flexible impulse vanes are securely locked together throughout their various portions so as to be rigidly held in proper position between the wheel rim and shroud ring outside.

It is of course desirable to have all the friction drive plates extend throughout the entire or practically the entire extent of the interposed impulse vanes so that any stepped back ends of the drive plates are given a curved form so that suitable supporting tongues or extensions, such as 54, are formed on these plates where they coöperate with the impulse vanes as shown at the bottom of Fig. 2. It is of course understood that any desired number of turbine wheels provided with such friction drive plates or members may be arranged in different wheel chambers so as to have as many stages as desired and thus more effectively utilize the energy of the motive fluid either with or without any other form of blades or vanes on the wheels. It is however desirable to arrange suitable impulse blades on the turbine wheels in connection with the friction drive plates or members described so as to utilize a greater proportion of the energy of the motive fluid in a single wheel and thus minimize the number of stages required for the desired turbine efficiency. As shown in Figs. 2 and 3, for example, a series of impulse blades such as 16, may be arranged between the wheel rim and shroud ring so as to be acted upon by the steam or other motive fluid after it has passed through the friction drive members and utilize an additional amount of its energy after its velocity has been considerably reduced. Any suitable number and shape of impulse blades may be used in this connection, a somewhat diagrammatic form of blade being shown in the drawing as arranged in line with each of the sets of primary impulse vanes and also interposed between them so as to form a larger number of blade passages 21 which turn the motive fluid so as to discharge it from the wheel laterally at relatively low velocity. In this way a gradual flaring passage for the motive fluid is formed extending forward and across the wheel, the motive fluid in the first part of its passage acting on friction drive members preferably having a slight impulse action and then acting on a second set of impulse blades before being discharged from the wheel. It is possible in this way, as is usually desirable, to have the steam path through the friction and blade members arranged with a constantly increasing area as to compensate for the gradual loss of velocity as the steam passes across the wheel. For this reason the wheel rim and shroud ring may be formed with portions, such as 49,

adjacent the beveled or sharpened stepped back discharge ends 24 of the friction drive plates so that the effective area of this portion 26 of the passage may be correspondingly adjusted. The action may be readily seen by reference to Fig. 2, the steam from the upper nozzle illustrated moving along the line A—A as it enters the wheel members and allowing for the forward movement of the wheel, passing along some such modified curved line as B B, as indicated by the arrows, the first part of its path through the friction drive portion of the wheel taking place in approximately the direction at which the motive fluid entered the wheel while it is subsequently directed laterally to a greater and greater extent by engagement with the forward sides of the primary impulse vanes or members which also tends to increase the frictional action of the motive fluid on the adjacent portions of the friction drive plates. The lower stage wheels, such as 9, may be arranged with similar friction drive plates or members 17 and subsequently acting impulse members such as 18 which are proportioned so as to act effectively on the larger volume of fluid issuing from the nozzles 13 coöperating with this wheel. If desired also each wheel may be arranged with several rows of impulse blades as shown in Fig. 5 where the wheel rim is shown as extended so as to support a series of friction drive plates or members 35 and the first set of impulse blades 36 in connection therewith and also a second set of impulse blades 38 spaced away from the first so that the direction of the motive fluid may be reversed by an interposed series of stationary reversing blades, such as 37. If desired, these reversing blades may be supported on suitable extensions 33 integral with or otherwise mounted on the nozzle members 45, although they may of course be supported in any other suitable way. Such an arrangement of course utilizes in a single wheel a still larger proportion of the energy of the motive fluid so as to be more desirable for some simple single stage turbine constructions.

This invention has been described in connection with a number of illustrative embodiments, forms, arrangements, proportions, materials, and parts, to the details of which disclosure the invention is not of course to be limited, since what is claimed as new and what is desired to be secured by Letters Patent is set forth in the appended claims.

1. In elastic fluid turbines, a nozzle member having expanding nozzles, a coöperating turbine wheel having a wheel rim, a shrouding ring supported in connection with said wheel rim to form a flaring annular passage extending across the wheel, a series of thin annular friction drive plates arranged in

spaced relation in said flaring passage, a series of curved impulse vanes interposed between adjacent friction drive plates and formed with integral retaining lugs to interlock with sockets in said plates, the receiving ends of said plates being beveled and arranged in inclined stepped back position to be engaged progressively by the motive fluid entering said flaring passage to provide a series of narrow channels for the motive fluid of progressively increasing width as the motive fluid moves across the wheel, there being projecting supporting tongues on the stepped back ends of said plates to coöperate with the ends of said interposed vanes, and a series of impulse blades arranged between said wheel rim and said shrouding ring beyond the discharge ends of said friction drive plates to be acted on by the motive fluid discharged by the frictional drive members.

2. In elastic fluid turbines, a nozzle member having nozzles, a coöperating turbine wheel having a wheel rim, a shrouding ring supported in connection with said wheel rim to form a flaring annular passage extending across the wheel, a series of thin friction drive plates arranged in spaced relation in said flaring passage, a series of curved impulse vanes interposed between adjacent friction drive plates and formed with integral retaining lugs to interlock with sockets in said plates, the receiving ends of said plates being beveled and arranged in inclined stepped back position to be engaged progressively by the motive fluid entering said flaring passage to provide a series of narrow channels for the motive fluid of progressively increasing width as the motive fluid moves across the wheel, and a series of impulse blades arranged between said wheel rim and said shrouding ring beyond the discharge ends of said friction drive plates to be acted on by the motive fluid discharged by the frictional drive members.

3. In elastic fluid turbines, a nozzle member having nozzles, a coöperating turbine wheel having a wheel rim, a shrouding ring supported in connection with said wheel rim to form a flaring annular passage extending across the wheel, a series of thin friction drive plates arranged in spaced relation in said flaring passage, a series of curved impulse vanes interposed between adjacent friction drive plates to provide a series of narrow channels for the motive fluid of increasing width as the motive fluid moves across the wheel, and a series of impulse blades beyond the discharge ends of said friction drive plates to be acted on by the motive fluid discharged by the frictional drive members.

4. In elastic fluid turbines, a turbine wheel having a wheel rim, a shrouding ring supported in connection with said wheel rim to form a

- 4
- flaring annular passage extending across the wheel, a series of thin annular friction drive plates arranged in spaced relation in said flaring passage, a series of curved impulse vanes interposed between adjacent friction drive plates and formed with integral retaining lugs to interlock with sockets in said plates, the receiving ends of said plates being beveled and arranged in inclined stepped back position to be engaged progressively by the motive fluid entering said flaring passage to provide a series of narrow channels for the motive fluid as the motive fluid moves across the wheel.
5. In elastic fluid turbines, a turbine wheel having a wheel rim, a shrouding ring supported in connection with said wheel rim to form a flaring annular passage extending across the wheel, a series of thin annular friction drive plates arranged in spaced relation in said flaring passage, a series of curved impulse vanes interposed between adjacent friction drive plates and formed with integral retaining lugs to interlock with sockets in said plates to provide a series of narrow channels for the motive fluid as the motive fluid moves across the wheel.
6. In elastic fluid turbines, a turbine wheel having an annular passage extending across the wheel, a series of thin annular friction drive plates arranged in spaced relation in said passage, a series of curved impulse vanes interposed between adjacent friction drive plates and formed with integral retaining lugs to interlock with sockets in said plates to provide a series of narrow channels for the motive fluid as the motive fluid moves across the wheel.
7. In elastic fluid turbines, a turbine wheel having an annular passage extending across the wheel, a series of thin annular friction drive plates arranged in spaced relation in said passage, a series of impulse vanes interposed between adjacent friction drive plates and formed with integral retaining lugs to interlock with sockets in said plates to provide a series of narrow channels for the motive fluid as the motive fluid moves across the wheel.
8. In elastic fluid turbines, a turbine wheel having an annular passage extending across the wheel, a series of thin friction drive plates arranged in spaced relation in said passage, a series of impulse vanes interposed between adjacent friction drive plates and formed with integral retaining means coöoperating with said plates to provide a series of narrow channels for the motive fluid as the motive fluid moves across the wheel.
9. In elastic fluid turbines, a turbine wheel having a wheel rim, a shrouding ring supported in connection with said wheel rim to form a flaring annular passage extending across the wheel, a series of thin annular friction drive plates arranged in spaced relation in said flaring passage, a series of curved impulse vanes interposed between adjacent friction drive plates and formed with integral retaining lugs to interlock with sockets in said plates, the receiving ends of said plates being beveled and arranged in inclined stepped back position to be engaged progressively by the motive fluid entering said flaring passage to provide a series of narrow channels for the motive fluid as the motive fluid moves through them across the wheel, there being projecting supporting tongues on the stepped back ends of said plates to coöperate with the ends of said interposed vanes.
10. In elastic fluid turbines, a turbine wheel having a wheel rim, a shrouding ring supported in connection with said wheel rim to form a flaring annular passage extending across the wheel, a series of thin friction drive plates arranged in spaced relation in said flaring passage, a series of impulse vanes interposed between adjacent friction drive plates and formed with integral retaining lugs to interlock with sockets in said plates, the receiving ends of said plates being beveled and arranged in inclined stepped back position to be engaged progressively by the motive fluid entering said flaring passage to provide a series of narrow channels for the motive fluid of progressively increasing width as the motive fluid moves through them across the wheel, there being projecting supporting tongues on the stepped back ends of said plates to coöperate with the ends of said interposed vanes.
11. In elastic fluid turbines, a turbine wheel having a wheel rim, a shrouding ring supported in connection with said wheel rim to form a flaring annular passage extending across the wheel, a series of thin friction drive plates arranged in spaced relation in said flaring passage, a series of impulse vanes interposed between adjacent friction drive plates and formed with integral retaining lugs to interlock with sockets in said plates, the receiving ends of said plates being arranged in stepped back position to be engaged progressively by the motive fluid entering said flaring passage to provide a series of narrow channels for the motive fluid of increasing width as the motive fluid moves through them across the wheel, there being projecting supporting tongues on the stepped back ends of said plates to coöperate with the ends of said interposed vanes.
12. In elastic fluid turbines, a turbine wheel having a flaring passage extending across the wheel, a series of thin friction drive plates arranged in spaced relation in said flaring passage, a series of impulse vanes interposed between adjacent friction

drive plates and formed with integral retaining lugs to interlock with sockets in said plates, the receiving ends of said plates being arranged in stepped back position to

5 be engaged progressively by the motive fluid entering said flaring passage to provide a series of narrow channels for the motive fluid of increasing width as the motive fluid moves through them across the wheel, there
10 being projecting supporting tongues on the stepped back ends of said plates to coöperate with said interposed vanes.

13. In elastic fluid turbines, a turbine wheel having a flaring passage extending 15 across the wheel, a series of thin friction drive plates arranged in spaced relation in said flaring passage, a series of impulse vanes interposed between adjacent friction drive plates and formed with integral retaining lugs to interlock with sockets in said plates, the receiving ends of said plates being arranged in stepped back position to be engaged progressively by the motive fluid entering said flaring passage to provide
20 a series of narrow channels for the motive fluid of increasing width as the motive fluid moves through them across the wheel.

14. In elastic fluid turbines, a turbine wheel having a wheel rim, a shrouding ring 30 supported in connection with said wheel rim to form a flaring annular passage, a series of thin friction drive plates arranged in spaced relation in said flaring passage, a series of impulse vanes interposed between
35 adjacent friction drive plates and formed with integral retaining lugs to interlock with sockets in said plates, the receiving ends of said plates being beveled and arranged in inclined stepped back position to
40 be engaged progressively by the motive fluid entering said flaring passage to provide a series of narrow channels for the motive fluid of progressively increasing width as the motive fluid moves through them, there
45 being projecting supporting tongues on the stepped back ends of said plates to coöperate with the ends of said interposed vanes.

15. In elastic fluid turbines, a turbine wheel having a wheel rim, a shrouding ring 50 supported in connection with said wheel rim to form a flaring annular passage, a series of thin friction drive plates arranged in spaced relation in said flaring passage, a series of impulse vanes interposed between
55 adjacent friction drive plates and formed with integral retaining lugs to interlock with sockets in said plates, the receiving ends of said plates being arranged in stepped back position to be engaged pro-
60 gressively by the motive fluid entering said flaring passage to provide a series of narrow channels for the motive fluid of increasing width as the motive fluid moves through them, there being projecting supporting
65 tongues on the stepped back ends of said

plates to coöperate with the ends of said interposed vanes.

16. In elastic fluid turbines, a turbine wheel having a flaring passage, a series of thin friction drive plates arranged in spaced relation in said flaring passage, a series of impulse vanes interposed between adjacent friction drive plates and formed with integral retaining lugs to interlock with sockets in said plates, the receiving ends of said plates being arranged in stepped back position to be engaged progressively by the motive fluid entering said flaring passage to provide a series of narrow channels for the motive fluid of increasing width as the motive fluid moves through them, there being projecting supporting tongues on the stepped back ends of said plates to coöperate with said interposed vanes.

17. In elastic fluid turbines, a turbine 85 wheel having a flaring passage, a series of thin friction drive plates arranged in spaced relation in said flaring passage, a series of impulse vanes interposed between adjacent friction drive plates and formed with integral retaining lugs to interlock with sockets in said plates, the receiving ends of said plates being arranged in stepped back position to be engaged progressively by the motive fluid entering said flaring passage 90 to provide a series of narrow channels for the motive fluid of increasing width as the motive fluid moves through them.

18. In elastic fluid turbines, a turbine wheel having a wheel rim, a shrouding ring 100 supported in connection with said wheel rim to form a flaring annular passage extending across the wheel, a series of thin annular friction drive plates arranged in spaced relation in said flaring passage, a series of curved impulse vanes interposed between adjacent friction drive plates, the receiving ends of said plates being beveled to be engaged by the motive fluid entering said flaring passage to provide a series of narrow 105 channels for the motive fluid of progressively increasing width as the motive fluid moves across the wheel.

19. In elastic fluid turbines, a turbine wheel having a wheel rim, a shrouding ring 115 supported in connection with said wheel rim to form a flaring annular passage extending across the wheel, a series of thin annular friction drive plates arranged in spaced relation in said flaring passage to provide a 120 series of narrow channels for the motive fluid of progressively increasing width as the motive fluid moves across the wheel.

20. In elastic fluid turbines, a turbine wheel having a wheel rim, a shrouding ring 125 supported in connection with said wheel rim to form a flaring annular passage extending across the wheel, a series of thin friction drive plates arranged in spaced relation in said flaring passage to provide a series of 130

8
narrow channels for the motive fluid of increasing width as the motive fluid moves across the wheel.

21. In elastic fluid turbines, a turbine wheel having a wheel rim, a shrouding ring supported in connection with said wheel rim to form a flaring annular passage extending across the wheel, a series of thin friction drive plates arranged in spaced relation in said flaring passage, the receiving ends of said plates arranged in stepped back position to be engaged progressively by the motive fluid entering said flaring passage to provide a series of narrow channels for the motive fluid of increasing width as the motive fluid moves across the wheel.

22. In elastic fluid turbines, a turbine wheel having a wheel rim, a shrouding ring supported in connection with said wheel rim to form a flaring annular passage extending across the wheel, a series of thin friction drive plates arranged in spaced relation in said flaring passage, the receiving ends of said plates being beveled and arranged in stepped back position to be engaged progressively by the motive fluid entering said flaring passage to provide a series of narrow channels for the motive fluid of increasing width as the motive fluid moves across the wheel.

23. In elastic fluid turbines, a turbine wheel having a flaring annular passage extending across the wheel, a series of thin welded annular friction drive members arranged in spaced relation in said passage, a series of interposed impulse vanes to provide a series of narrow channels for the motive fluid of progressively increasing width as the motive fluid moves across the wheel.

24. In elastic fluid turbines, a turbine wheel having an annular passage extending across the wheel, a series of thin welded annular friction drive members arranged in spaced relation in said passage to provide a series of narrow channels for the motive fluid as the motive fluid moves across the wheel.

25. In elastic fluid turbines, a turbine wheel having an annular passage extending across the wheel, a series of thin annular friction drive members arranged in spaced relation in said passage, to provide a series of narrow channels for the motive fluid as the motive fluid moves across the wheel.

26. In elastic fluid turbines, a turbine wheel having an annular passage extending across the wheel, a series of thin welded friction drive members arranged in spaced relation in said passage to provide a series of narrow channels for the motive fluid as the motive fluid moves across the wheel.

27. In elastic fluid turbines, a turbine wheel having a passage extending across the wheel, a series of friction drive members

arranged in said passage and having approximately parallel adjacent surfaces, to provide a series of narrow flaring channels free from abrupt changes of directions for the motive fluid as the motive fluid moves across the wheel, and a series of impulse blades arranged on said wheel to be acted on by the motive fluid discharged by the frictional drive members, the effective area of said channels and the passages between said impulse blades varying in substantial proportion to the decrease of velocity of the motive fluid as it moves across the wheel.

28. In elastic fluid turbines, a turbine wheel having a flaring passage extending across the wheel, a series of thin friction drive plates arranged in spaced relation in said flaring passage, a series of impulse vanes interposed between adjacent friction drive plates and formed with integral retaining lugs to interlock with sockets in said plates, the receiving ends of said plates being arranged in stepped back position to be engaged progressively by the motive fluid entering said flaring passage to provide a series of narrow channels for the motive fluid of increasing width as the motive fluid moves through them across the wheel, there being projecting supporting tongues on the stepped back ends of said plates to cooperate with said interposed vanes, and a series of impulse blades arranged on said wheel to be acted on by the motive fluid discharged by the frictional drive members.

29. In elastic fluid turbines, a turbine wheel having a flaring passage extending across the wheel, a series of thin friction drive plates arranged in spaced relation in said flaring passage, a series of impulse vanes interposed between adjacent friction drive plates and formed with integral retaining lugs to interlock with sockets in said plates, the receiving ends of said plates being arranged in stepped back position to be engaged progressively by the motive fluid entering said flaring passage to provide a series of narrow channels for the motive fluid of increasing width as the motive fluid moves through them across the wheel, and a series of impulse blades arranged on said wheel to be acted on by the motive fluid discharged by the frictional drive members.

30. In elastic fluid turbines, a turbine wheel having a flaring passage, a series of thin friction drive plates arranged in spaced relation in said flaring passage, a series of impulse vanes interposed between adjacent friction drive plates and formed with integral retaining lugs to interlock with sockets in said plates, the receiving ends of said plates being arranged in stepped back position to be engaged progressively by the motive fluid entering said flaring passage to provide a series of narrow channels for the

motive fluid of increasing width as the motive fluid moves through them, there being projecting supporting tongues on the stepped back ends of said plates to co-operate with said interposed vanes, and a series of impulse blades arranged on said wheel to be acted on by the motive fluid discharged by the frictional drive members.

31. In elastic fluid turbines, a turbine wheel having a flaring passage, a series of thin friction drive plates arranged in spaced relation in said flaring passage, a series of impulse vanes interposed between adjacent friction drive plates and formed with integral retaining lugs to interlock with sockets in said plates, the receiving ends of said plates being arranged in stepped back position to be engaged progressively by the motive fluid entering said flaring passage to provide a series of narrow channels for the motive fluid of increasing width as the motive fluid moves through them, and a series of impulse blades arranged on said wheel to be acted on by the motive fluid discharged by the frictional drive members.

32. In elastic fluid turbines, a turbine wheel having a wheel rim, a shrouding ring supported in connection with said wheel rim to form a flaring annular passage extending across the wheel, a series of thin friction drive plates arranged in spaced relation in said flaring passage to provide a series of narrow channels for the motive fluid of increasing width as the motive fluid moves across the wheel, and a series of impulse blades arranged on said wheel to be acted on by the motive fluid discharged by the frictional drive members.

33. In elastic fluid turbines, a turbine wheel having a wheel rim, a shrouding ring supported in connection with said wheel rim to form a flaring annular passage extending across the wheel, a series of thin friction drive plates arranged in spaced relation in said flaring passage, the receiving ends of said plates arranged in stepped back position to be engaged progressively by the motive fluid entering said flaring passage to provide a series of narrow channels for the motive fluid of increasing width as the motive fluid moves across the wheel, and a series of impulse blades arranged on said wheel to be acted on by the motive fluid discharged by the frictional drive members.

34. In elastic fluid turbines, a turbine wheel having an annular passage extending across the wheel, a series of thin welded friction drive members arranged in spaced relation in said passage to provide a series of narrow channels for the motive fluid as the motive fluid moves across the wheel, and a series of impulse blades arranged on said wheel to be acted on by the motive fluid discharged by the frictional drive members.

35. In elastic fluid turbines, a turbine

wheel having a passage extending across the wheel, a series of friction drive members arranged in said passage and having approximately parallel adjacent surfaces, to provide a series of narrow channels free from abrupt changes of direction for the motive fluid as the motive fluid moves across the wheel, and a series of impulse blades arranged on said wheel to be acted on by the motive fluid discharged by the frictional drive members.

36. In elastic fluid turbines, a turbine wheel having a wheel rim, a shrouding ring supported in connection with said wheel rim to form a flaring annular passage extending across the wheel, a series of thin friction drive plates arranged in spaced relation in said flaring passage to provide a series of narrow channels for the motive fluid of increasing width as the motive fluid moves across the wheel, and a series of impulse blades arranged on said wheel to be acted on by the motive fluid discharged by the frictional drive members, and a plurality of annular series of impulse blades arranged on said wheel to be acted on by the motive fluid discharged from the frictional drive members and interposed stationary reversing blades between each successive series of impulse blades.

37. In elastic fluid turbines, a turbine wheel having a wheel rim, a shrouding ring supported in connection with said wheel rim to form a flaring annular passage extending across the wheel, a series of thin friction drive plates arranged in spaced relation in said flaring passage, the receiving ends of said plates arranged in stepped back position to be engaged progressively by the motive fluid entering said flaring passage to provide a series of narrow channels for the motive fluid of increasing width as the motive fluid moves across the wheel, and a plurality of annular series of impulse blades arranged on said wheel to be acted on by the motive fluid discharged from the frictional drive members and interposed stationary reversing blades between each successive series of impulse blades.

38. In elastic fluid turbines, a turbine wheel having an annular passage extending across the wheel, a series of thin welded friction drive members arranged in spaced relation in said passage to provide a series of narrow channels for the motive fluid as the motive fluid moves across the wheel, and a plurality of annular series of impulse blades arranged on said wheel to be acted on by the motive fluid discharged from the frictional drive members and interposed stationary reversing blades between each successive series of impulse blades.

39. In elastic fluid turbines, a turbine wheel having a passage extending across the wheel, a series of friction drive members ar-

- ranged in said passage, to provide a series of narrow channels for the motive fluid as the motive fluid moves across the wheel, and a plurality of annular series of impulse blades arranged on said wheel to be acted on by the motive fluid discharged from the frictional drive members and interposed stationary reversing blades between each successive series of impulse blades.
- 10 40. In elastic fluid turbines, a turbine wheel having a flaring passage extending across the wheel, a series of thin friction drive plates arranged in spaced relation in said flaring passage, a series of impulse vanes interposed between adjacent friction drive plates and formed with integral retaining lugs to interlock with sockets in said plates, the receiving ends of said plates being arranged in stepped back position to be engaged progressively by the motive fluid entering said flaring passage to provide a series of narrow channels for the motive fluid of increasing width as the motive fluid moves through them across the channel, the effective area of said channels varying in substantial proportion to the decrease of velocity of the motive fluid as it moves across the wheel.
- 15 41. In elastic fluid turbines, a turbine wheel having a wheel rim, a shrouding ring supported in connection with said wheel rim to form a flaring annular passage extending across the wheel, a series of thin friction drive plates arranged in spaced relation in said flaring passage to provide a series of narrow channels for the motive fluid of in-

creasing width as the motive fluid moves across the wheel, the effective area of said channels varying in substantial proportion to the decrease of velocity of the motive fluid as it moves across the wheel.

42. In elastic fluid turbines, a turbine wheel having a flaring passage, a series of thin friction drive plates arranged in spaced relation in said flaring passage, a series of impulse vanes interposed between adjacent friction drive plates and formed with integral retaining lugs to interlock with sockets in said plates, the receiving ends of said plates being arranged in stepped back position to be engaged progressively by the motive fluid entering said flaring passage to provide a series of narrow channels for the motive fluid of increasing width as the motive fluid moves through them, there being projecting supporting tongues on the stepped back ends of said plates to cooperate with said interposed vanes, and a series of impulse blades arranged on said wheel to be acted on by the motive fluid discharged by the frictional drive members, the effective area of said channels and the passages between said impulse blades varying in substantial proportion to the decrease of velocity of the motive fluid as it moves across the wheel.

CHARLES BEMIS REARICK.
